UNITED STATES PATENT OFFICE.

OF PHILADELPHIA, PA.

DESIGN FOR OIL-CLOTH.

Specification forming part of Design No. **11,311**, dated August 5, 1879; application filed July 9, 1879.
[Term of patent 3½ years.]

To all whom it may concern:

Be it known that I, JOSEPH BARRETT, of New York city, have produced or invented a new and original Design for an Oil-Cloth Pattern, of which the following is a specification.

My design for an oil-cloth pattern is fully shown in the accompanying photographic illustration.

The design comprises square figures A and B. The figures A have central panels, *a*, veined in imitation of marble, and each corner of the figure is occupied by a segmental figure, *b*, of the character shown. The figures B are crossed diagonally in both directions by broad bands *d*, and where these bands cross each other in

the center of the figures B are formed square figures *e*, each ornamented with a central rosette, as shown.

Irrespective of the colors employed, I claim—

The design for an oil-cloth pattern, substantially as described, and as shown in and by the accompanying photographic illustration.

In testimony whereof I have signed my name to this specification in the presence of two subscribing witnesses.

JOSEPH BARRETT.
